UNITED STATES PATENT OFFICE

152,060

DESIGN FOR A CAN PUNCH

Walter A. Campion, South St. Paul, Minn.

Application January 23, 1947, Serial No. 136,316

Term of patent 3½ years

(Cl. D22—2)

To all whom it may concern:

Be it known that I, Walter A. Campion, a citizen of the United States, residing at South St. Paul, county of Dakota, and State of Minnesota, have invented a new, original, and ornamental Design for a Can Punch, of which the following is a specification, reference being had to the accompanying drawing, forming part thereof.

Figure 1 is a top perspective view of a can punch, showing my new design;

and

Figure 4 is a bottom plan view of the same.

I claim:

The ornamental design for a can punch, as shown.

WALTER A. CAMPION.
